United States Patent Office

Des. 196,945
Patented Nov. 19, 1963

196,945

PICNIC CHEST

Harold V. Tibbets, Houston, Tex., assignor to Texas Tennessee Industries, Inc., Houston, Tex., a corporation of Texas

Filed May 10, 1963, Ser. No. 74,838

Term of patent 14 years

(Cl. D58—17)

Fig. 1

Fig. 2

Fig. 3

Fig. 4

Fig. 5

Fig. 6

I claim:

The ornamental design for a picnic chest, substantially as shown.
